Primary Examiner — Catherine S Posthauer*Assistant Examiner* — Alison M Ofstun(74) *Attorney, Agent, or Firm* — Saliwanchik, Lloyd & Eisenschken(57) **CLAIM**

The ornamental design for a vacuum generator, as shown and described.

DESCRIPTION

FIG. 1 is a perspective view of a vacuum generator showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

In the drawings, the broken lines represent portions of the article which form no part of the claimed design.
